(57) **CLAIM**

We claim the ornamental design for a light-emitting diode lamp, as shown and described.

DESCRIPTION

FIG. 1 is a top perspective view of a first embodiment of a light-emitting diode lamp of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a sectional view taken along the line 8-8 of FIG. 2 thereof;

FIG. 9 is a top perspective view of a second embodiment of a light-emitting diode lamp of the present invention;

FIG. 10 is a front view thereof;

FIG. 11 is a rear view thereof;

FIG. 12 is a first side view thereof;

FIG. 13 is a second side view thereof;

FIG. 14 is a top view thereof;

FIG. 15 is a bottom view thereof; and,

FIG. 16 is a sectional view taken along the line 16-16 of FIG. 10 thereof.

The broken line showing of light-emitting diode lamp is included for the purpose of illustrating environment and forms no part of the claimed design.

It is understood that the bracketed portion represents indeterminate length.
